UNITED STATES PATENT OFFICE.

OLIVER P. TEEPLE, OF BARBERTON, OHIO, ASSIGNOR TO THE DIAMOND MATCH COMPANY, OF CHICAGO, ILLINOIS, A CORPORATION OF ILLINOIS.

MACHINE FOR MAKING REINFORCED BOX TRAYS.

Application filed April 9, 1921. Serial No. 459,844.

To all whom it may concern:

Be it known that I, OLIVER P. TEEPLE, a citizen of the United States, and resident of Barberton, in the county of Summit and 5 State of Ohio, have invented certain new and useful Improvements in Machines for Making Reinforced Box Trays, of which the following is a specification.

This invention relates to machines for 10 making reinforced box-trays, having reference especially to the machine forming the subject-matter of Letters Patent of the United States No. 1,293,288, dated February 4, 1919.

15 The machine described in said patent includes mechanism for intermittently feeding a strip of box stock, means for producing spaced-apart recesses in the respective edges of the strip to provide longitudinal side laps integral with the body of the strip, means for folding said laps upon the adjacent parts of the strip body to provide reinforced side portions, and means for transversely severing the strip between succeeding reinforced portions. Such folding means comprises vibratory arms for partially folding the laps inward, stationary members for completing the folding of the laps upon the adjacent portions of the 20 strip, and a movable pressure device for acting upon the folded laps.

The present invention is in the nature of an improvement in or modification of the said folding means with the view of simplifying the mechanism and increasing the speed and consequently the output of the machine.

According to my invention I provide a novel cam construction which accomplishes 40 the folding and pressing of the side laps of the strip in a rapid and effective manner as the strip progresses from the lap forming to the strip severing mechanism, as will be hereinafter described and claimed.

45 In the drawings—

Figure 1 is a vertical section of a box-tray machine equipped with a lap-folding structure embodying my invention.

Fig. 2 is a plan of the said structure 50 showing the adjacent slitting and recessing die, and also the strip of stock which is being acted upon; parts of the longitudinal cam bars being broken away.

Figs. 3 to 6, inclusive, are transverse sections on the respective lines, 3—3, &c., of

Fig. 2, showing the progressive lap-folding operations.

Fig. 7 is a perspective view of the receiving end of the lap-folding structure as detached and with the longitudinal cam bars 60 removed, showing a progressing strip of box stock.

Fig. 8 is a similar view of the separate parts of the strip-receiving end of the structure.

Fig. 9 is a similar view of one of the longitudinal cam bars.

Referring to the drawings, 11 designates a supporting frame, including the table 12.

13 designates the main shaft; 14 a glue-pot suitably located beneath the table; 15 one of the spaced die-plates at the rear of the table, and 16 a plunger carrying punches 17 which are reciprocative through the openings of the die plates.

18 designates a roll from which the strip, A, of box stock is drawn to and across the roll of the glue pot, and thence about suitable guide rollers into the path between the die-plates 15 so as to be acted upon by the 80 punches 17 at spaced intervals throughout the length of the strip. The punches are of such character as to produce in the strip longitudinal, parallel slits *d* and lateral offsets or recesses *e* to define the spaced reinforcing side laps *f*, corner tongues *g* and end folds *h* for succeeding box trays. The side portions of the strip adjacent the laps are supplied with glue which cements the laps to the strips when they are folded over 85 upon such side portions.

18' designates a pair of intermittently-rotatable feeding and scoring rolls by means of which longitudinal score lines *c* are formed in the strip preparatory to the action of the punches, and by which rolls the strip is intermittently fed through the die-path and along the top of the table 12, each impulse of the strip being equal to the length of a tray blank, all as fully set forth 100 in Patent No. 1,293,288 aforesaid.

The improved folding devices to the action of which the reinforcing side laps *f* are subjected after they have passed beyond the punch and die devices, is of 105 the following construction:

19 designates an elongated block of inverted V-form in cross-section having a basal plate extension 20 at one end and an angular bracket portion 21 at the opposite end.

This bracket is bolted to the die-plate, as at 21', so that the base of the block longitudinally overhangs the top of the table and extends in spaced parallel relation thereto, so 5 as to provide a free passage for the strip. Secured to the oppositely-inclined faces of the block are two plates 22 the lower edges of which extend freely beyond the block and in close parallel relation to the fold lines of 10 the respective laps f of the strip. The plates are preferably secured in place by set-screws 23, the holes 24 for which in the plates are elongated so as to permit relative adjustment of the lower edges of the plates as desired. The lower corners of the plates 22, adjacent the bracket 21, are turned slightly upward to provide lap-guiding members 25, and the opposite ends of the plates are provided with lap supporting tongues 26 constituting extensions of the lower edges of 20 the plates.

Secured to the table, in spaced parallel relation to each other and to the lower edges of the respective plates 22, are two longitudinally extending bars 27 having inwardly extending cam portions, which are located in the longitudinal paths of the respective side laps of the strip and are so shaped as to receive the opposing laps and gradually bend 25 them inward and downward in a manner to fold the laps upon the adjacent side portions of the progressing strip. The cam portions of the bars at their right hand or receiving end, as viewed in Fig. 2, are spaced apart 30 sufficiently to permit the entry of the advancing side laps under the respective cam portions, as indicated at 28, which portions gradually incline above and overlie the lower edges of the inclined side plates, as at 35 29, and then gradually assume a horizontal position and extend thus in spaced parallel relation to the top of the table, as at 30, and near to the transverse feeding and scoring rolls 31. These rolls are arranged in the vicinity of the vertically-reciprocatative knife 32 40 by means of which the strip is severed into blanks designed to be subsequently formed 45 into box trays in any suitable manner.

By the novel folding devices above described it will be seen that as the strip of box stock progresses from the punch and die mechanism the outer edges of the respective laps f of the strip pass between the end portions of the cam bars, and thence along the 50 cam portions 29 of the latter, the laps thus being gradually bent toward and against the free lower edges of the plates 22 and inwardly upon the inclined faces of the plates, and that said laps when they escape the extensions 55 60 of the plates are gradually folded down and firmly pressed upon the underlying side portions of the strip for an extended

interval of time. Consequently as the strip progresses the laps thereof are not only rapidly and accurately folded but they are also 65 effectually cemented to the adjacent side portions of the strip preparatory to the severing operation of the cutting mechanism.

I claim—

1. In a box-tray machine having mechanism for feeding a strip of material provided with spaced reinforcing side laps, a lap-folding structure comprising oppositely inclined plates, means supporting said plates, and parallel cam bars located in the 70 longitudinal paths of the respective side laps of the progressing strip, each of said cam bars having a portion which gradually inclines toward and above the lower edges of the inclined plates and then gradually assumes a horizontal position and extends thus in close parallel relation to the strip.

2. In a box-tray machine having mechanism for feeding a strip of material provided with spaced reinforcing side laps, a lap-folding structure comprising a stationary elongated block of inverted V-form in cross-section having a flat basal portion adjacent the path of the strip, plates secured to the inclined surfaces of the block, and parallel cam 75 bars located in the longitudinal paths of the respective side laps of the progressing strip, each of said cam bars having a portion which gradually inclines toward and above the lower edges of the inclined plates and 80 then gradually assumes a horizontal position and extends thus in close parallel relation to the strip.

3. In a box-tray machine having mechanism for feeding a strip of material provided with spaced reinforcing side laps, a lap-folding structure comprising a stationary elongated block of inverted V-form in cross-section and having a flat basal portion 100 adjacent the path of the strip, plates secured to the inclined surfaces of the block, the lower corners of said plates adjacent the receiving end of the structure being turned 105 slightly upward to provide lap-guiding members and the opposite ends of said plates 110 being extended to provide lap-supporting tongues, and parallel cam bars located in the longitudinal paths of the respective side laps, each of said cam bars having a portion which gradually inclines toward and above 115 the lower edges of the inclined plates and then gradually assumes a horizontal position and extends thus in close parallel relation to the strip.

Signed at Barberton, in the county of 120 Summit, and State of Ohio this 1 day of April A. D., 1921.

OLIVER P. TEEPLE.
